CARPET SWEEPER CONSTRUCTION

Filed Sept. 29, 1934

UNITED STATES PATENT OFFICE

2,011,262

CARPET SWEEPER CONSTRUCTION

Fred W. Pullen, Grand Rapids, Mich., assignor to
Bissell Carpet Sweeper Company, Grand Rap-
ids, Mich.

Application September 29, 1934, Serial No. 746,183

3 Claims. (Cl. 15—41)

The objects of this invention are:

First, to provide a new and improved carpet sweeper construction in which the floor wheels and the ends of the case and operating parts are concealed.

Second, to provide such a construction having a sheet metal end plate extending over the wheels and concealing the end of the case.

Third, to provide such a construction in which a pan dump lever and the wheels are concealed by a sheet metal end plate and in which the concealed dump lever is made easily accessible though concealed.

Other objects and advantages pertaining to details and economies of construction and operation will appear from the description to follow. A preferred embodiment of my invention is illustrated in the accompanying drawing, in which:

Fig. 1 is a plan view of the carpet sweeper embodying my invention.

Fig. 2 is a sectional view taken on line 2—2 of Fig. 1 but omitting the corner bumpers and cord surrounding the sweeper.

Fig. 3 is a detail sectional view taken on line 3—3 of Fig. 2.

Fig. 4 is a fragmentary end view of the corner of a sweeper showing the method of attaching the end plate.

In the drawing, 1 is a carpet sweeper case having a top 2, ends 3 and side rails 4. The top 2 of the sweeper shown is of sheet metal having a flange 102 extending down over the ends 3 which are of wood. The flange 102 has an extension 202 which serves as a bearing plate to engage the lever 22 and the plate 34, as is shown in Fig. 3. The flange 102 is cut away just above the fulcrum 23 of the lever 22 in the specific sweeper shown. If the flange 102 is sufficiently narrow, it need not be cut away as indicated. 5 is the cord surrounding the sweeper and 6 are rubber corner bumpers through which the cord passes. 7 is the bail and 8 the handle. 9 are the floor wheels which engage the hub 10 of the brush 11 for driving the same. 12 are equalizer levers such as are illustrated in my Patent No. 1,786,864, issued December 30, 1930, for Carpet sweeper brush guide mechanism. 13 is the slide to which the brush 11 is pivoted by pin 14, and 15 and 16 are the slots of the equalizer lever 12. I have not detailed this mechanism because it is not an essential part of this invention.

17 are dust pans pivoted at 18 and provided with an A-shaped spring 19 fastened in holes 20 in the downwardly and inwardly projecting ends of the pan. The apex 21 of the spring clears the

top 2 of the case to engage a lever 22. This lever corresponds substantially in construction to the lever shown in my Patent No. 1,933,758, issued November 7, 1933, and comprises a single rod or heavy wire having an offset central pivot portion 23 disposed through slightly enlarged aperture 24 in the end of the case and which is filled with a clip 25. The lever has flattened portions 26, 27 for strengthening the same and the end 28 is formed as is indicated in said patent by flattening the wire or rod. A lug 29 engages the A-shaped member 19 and by depressing the end 28 of the lever, the dust pans are dumped in the usual manner.

Spaced from the end of the case and lying beyond the wheels is end plate 30. The end plate 30 is of metal and has an inwardly extending flange at the top. The flange extends toward the sweeper top 3 and is of substantially the same contour as that top. As is shown in Fig. 3, plate 30 extends downwardly outside of the wheels at the end of the sweeper case and practically conceals the wheels. At its upper edge it is provided with an inwardly turned flange 31 which extends over the floor wheels of the sweeper and toward the case and in the same plane as the top of the case. At the ends of the plate, the flange continues as at 32 and lies substantially in the plane of the sides of the sweeper case.

At the top of the plate 30 and in the upper flange 31, I provide an aperture 33 located adjacent the end 28 of the lever 22 for access thereto. On the end 28 of the lever 22, I provide a finger plate 34 which fits said aperture 33. This plate is spot-welded or otherwise affixed to the portion 28 of the lever 22. The lever 22 is so arranged that when the pans are in position for sweeping, the finger plate 34 lies substantially flush with the flange 31 and provides with that a substantially continuous surface, effectively concealing the dump lever and assisting in concealing the working parts of the sweeper.

The end plate 30 is affixed to the sweeper in any desired manner. In Fig. 4 I have shown a very satisfactory method. The ends 41 of the sides 4 of the sweeper case extend beyond the end of the case and the flange 32 at the side of the plate 30 extends over this extension 41 and is fastened by suitable nails 42 or the like extending through the openings 43 in the flange 32.

It will be understood that my improved construction presents a concealing end plate and that the dump lever 22 is almost fully concealed and is at the same time readily available for use, giving

a very trim appearance to a carpet sweeper embodying my improvements.

I have shown and described my improved construction in the embodiment preferred by me, but 5 wish to claim the same broadly as well as specifically, as pointed out in the appended claims.

Having thus described my invention, what I claim as new and desire to secure by Letters Patent is:

- 10 1. In a carpet sweeper having a case with floor wheels at the ends thereof and with dust pans and means for actuating them to dump them, the combination of a sheet metal end plate spaced from the end of the case and beyond the wheels 15 and of a contour substantially the same as the contour of the end of the case and substantially covering said end and its wheels to conceal the same, said plate having along its upper edge an inturned flange extending over said wheels and toward, and in the plane of, the top of the case and substantially closing the space between said plate and said case to conceal the wheels, said plate having along its ends continuations of said flange extending toward and in the planes of the 20 sides of the case, said flange at the upper edge of said plate having an aperture therein for access to a pan dump lever, a pan dump lever connected to said means for actuating said pans for dumping them and having one end lying between said case 25 and said plate, and a finger plate at the end of said pan dump lever and fitting in said aperture in said flange and lying flush with said flange when the pans are in position for sweeping, thereby forming with said flange and plate a substantially continuous surface.
- 20 2. In a carpet sweeper having a case with floor wheels at the ends thereof and with dust pans and means for actuating them to dump them, the combination of a sheet metal end plate spaced from the end of the case and beyond the wheels 25 and of a contour substantially the same as the contour of the end of the case and substantially covering said end and its wheels to conceal the same, said plate having along its upper edge an inturned flange extending over said wheels and toward, and in the plane of, the top of the case and substantially closing the space between said plate and said case to conceal the wheels, said plate having along its 30 upper edge an inturned flange extending over said wheels and toward the case and substantially closing the space between said plate and said case to conceal the wheels, said flange having an aperture therein for access to a pan dump lever, a pan 35 dump lever connected to said means for actuating said pans for dumping them and having one end lying between said case and said plate, and a finger plate at the end of said pan dump lever and fitting in said aperture in said flange when the pans are in position for sweeping, thereby forming with said flange and plate a substantially continuous surface.

from the end of the case and beyond the wheels and of a contour substantially the same as the contour of the end of the case and substantially covering said end and its wheels to conceal the same, said plate having along its upper edge an inturned flange extending over said wheels and toward, and in the plane of, the top of the case and substantially closing the space between said plate and said case to conceal the wheels, said flange having an aperture therein for access to a pan dump lever, a pan dump lever connected to said means for actuating said pans for dumping them and having one end lying between said case and said plate, and a finger plate at the end of said pan dump lever and fitting in said aperture in said flange and lying flush with said flange when the pans are in position for sweeping, thereby forming with said flange and plate a substantially continuous surface.

3. In a carpet sweeper having a case with floor 20 wheels at the ends thereof and with dust pans and means for actuating them to dump them, the combination of a sheet metal end plate spaced from the end of the case and beyond the wheels 25 to conceal the same, said plate having along its upper edge an inturned flange extending over said wheels and toward the case and substantially closing the space between said plate and said case to conceal the wheels, said flange having an aperture therein for access to a pan dump lever, a pan 30 dump lever connected to said means for actuating said pans for dumping them and having one end lying between said case and said plate, and a finger plate at the end of said pan dump lever and fitting in said aperture in said flange when 35 the pans are in position for sweeping, thereby forming with said flange and plate a substantially continuous surface.

FRED W. PULLEN.
